DESIGN FOR A SPIRIT LEVEL

William Arthur Honeyman, San Francisco, Calif.

Application April 15, 1944, Serial No. 113,251

Term of patent 7 years

(Cl. D52—1)

To all whom it may concern:

Be it known that I, William Arthur Honeyman, a citizen of the United States, residing at San Francisco, in the county of San Francisco and State of California, have invented a new, original, and ornamental Design for a Spirit Level, of which the following is a specification, reference being had to the accompanying drawing, forming part thereof.

The figure is a perspective view of a spirit level, showing my new design.

I claim:

The ornamental design for a spirit level, as shown.

WILLIAM ARTHUR HONEYMAN.
